UNITED STATES PATENT OFFICE

2,603,962

CLOTHES WRINGER

John V. Gunn, Tulsa, Okla.

Application May 3, 1948, Serial No. 24,900

1 Claim. (Cl. 68—262)

1

One object is to provide a wringer with a simple and efficient means for guiding fabrics to and between the expressing rolls, and providing in said means an incline sufficiently steep, by which the extracted water will flow downwardly over said means and back into the receptacle from which taken.

Another object is to provide a wringer with means whereby the pressure in the expressing rolls can be easily and quickly released, in case of an emergency, so as to open the pass between the expressing rolls and free any object gripped therein; and in the said means providing in the handle thereof, a safety guard to prevent the hand of the operator from inadvertently following the wet fabrics to the point of danger.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Drawings

In the accompanying drawings, the preferred form has been shown in which:

Figure 1 is an elevational front view of the wringer with a part cut away at the left showing relation of parts in the lower member "A."

Figure 2 is a sectional view, showing the moving and stationary parts and their relation to each other in that part of the wringer between the two heads.

Figure 3 is a sectional view, showing the moving and stationary parts and their relation to each other in the end heads.

Figure 4 is a perspective view of the upper member "B" fully assembled.

Figure 5 is a perspective view of the interlocking shaft with the handle removed.

Figure 6 is a perspective view of the holding blocks.

Figure 7 is a perspective view of the end heads showing the central and lateral channels together with the location of the interlocking blocks, connecting bars and inclined drainage belt bracket plate.

Referring to figures by characters of reference, "A" and "B" designate members constituting the wringer; "A" designating the lower member and "B" designating the upper member. A head 1, of any suitable contour, is provided centrally

2

with a vertical recess 2 (Fig. 7) extending from top to bottom thereof; and said recess 2 extending laterally into side channels 3 provided with shelves 4 about midway between top and bottom thereof. Within the lower portion of recess 2, one of the heads 1a is provided with a bearing 5 and socket 6 (Figs. 3 and 7) in which is journaled one of the gudgeons 7 (Fig. 2) of the lower expressing roll 8, while the opposite head 1 is provided with an opening through which passes the journal 9 (Fig. 1) of the opposite end of the lower expressing roll 8. Below the lower expressing roll 8 is provided an idler roll 10 (Fig. 2) journaled in one of the heads 15 by means of a bearing and socket, and in the opposite head by means of an adjustable bearing 11 and socket 12, held in place by a key pin 13.

From the lower corners of the wringer heads 1 and 1a, extend rotund connecting bars 14 which form part of the framework of the wringer and connect the two heads 1 and 1a. Extending from each of the rotund connecting bars 14 is a plate bracket 15 upwardly inclined toward the top of the lower expressing roll 8. An impervious endless belt 16 is provided which extends over this bracket 15 and over the lower expressing roll 8, thence downwardly over the opposite bracket 15 and partly around the opposite rotund connecting bar 14, thence upwardly and over the idler roll 10 where it is pressed tightly against the lower portion of the lower expressing roll 8, thence downwardly again and extending partly around the rotund connecting bar 14 and thence to the point of starting. The said bracket 15 is provided sufficiently steep to shed the water, extracted from the wet fabrics, down the incline of ascending impervious belt and into the receptacle from which taken.

In the upper portion of the head recess 2, and extending laterally into the side channels 3, is provided a holding block 18 (Fig. 6), said holding block consisting of two side shoulders 19 connected by a plate back 20. Vertically through the side shoulders 19 are openings 21 through which extend tension rods 22 held at the top of shoulders 19 by nuts 23 (Fig. 3). The tension rods 22 extend downwardly through openings 24 in the shelves 4 and into the lower portion of the channels 3 where, by means of rod heads 25, they support coiled tension springs 26. The coiled tension spring 26 is compressed upwardly against the shelf 4, and the rod 22 pulls down on the holding block 18. In the upper portion 50 of the holding block 18 and connecting plate back

20, is provided a vertical slot 27, the lower portion being provided with lateral extensions 28 forming shoulders 29, as a means of interlocking the upper member "B" to the lower member "A." This completes the lower member "A." And now follows the upper member "B."

Between the shoulders 19 of the holding block 18 are fitted bearing blocks 30 (Figs. 3 and 4) connected by a cross bar 31. The bearing blocks 30 are provided with ball bearings 32 adapted to receive the gudgeons 33 of the upper expressing roll 17 (Figs. 2 and 4). In the upper portion of the bearing blocks 30 is provided an opening 34, the bottom 35 of which is provided with two niches 36 used in the interlocking process.

The openings 34 in the bearing blocks 30 are adapted to receive the end-shoulders 37 of the interlocking shaft 38. The end-shoulders 37 of the interlocking shaft 38 are provided centrally with a pivot key 39, the two of which form a leverage for the lifting of the holding block 18 in the process of interlocking the upper member "B" to the lower member "A." The end shoulders 37 of the interlocking shaft 38 are adapted to rest upon the bottom 35 of the opening 34 while the pivot-key 39 extends into the slot side extension 28 and under the slot shoulders 29. When the interlocking shaft 38, which by means of arms 40 is connected to handle 41 is actuated by pulling the handle 41 forward and downward, the pivot-key 39 rises under the shoulder 29 of the slot side extension 28 of the holding block 18. In the process of interlocking the upper member "B" to the lower member "A," the point 42 of the shoulder 37 of the interlocking shaft 38, drops into the niche 36 immediately under the pivot-key 39 (Figs. 2 and 3), and the handle 41 rests upon the handle-stop 43 fixed to the head 1. Thus the upper expressing roll 17 is made to press against the lower expressing roll 8, and the two members "A" and "B" are interlocked and the wringer is ready for operation.

To release the upper expressing roll 17 from the lower expressing roll 8, a slight upward flick of the hand or wrist against the handle 41 forces the pivot-key 39 to move from under the slot-shoulder 29 and into the vertical slot 27; thereby removing all tension from the upper expressing roll 17 and allowing it to move away from the lower expressing roll 8, thus releasing whatever may have been caught between the two rolls.

What is claimed is:

In a clothes wringer, a pair of spaced heads; lower expressing roll bearings fixedly mounted on

the respective heads; holding blocks vertically slideable in the heads, each block having a vertical slot opening at one end thereof and having a horizontal extension slot communicating with said vertical slot; springs positioned beneath each block and within each head and normally urging the blocks in the direction of the lower expressing roll bearings; fixedly connected bearing blocks vertically slideable on the respective holding blocks, each bearing block having an opening, there being notches formed in one edge of the opening; upper expressing roll bearings mounted on said bearing blocks and spaced vertically of the first-named bearings; a locking shaft mounted in the respective bearing blocks and extending therebetween, said locking shaft having a rounded bottom portion rockably mounted in said openings in the bearing blocks, said shaft being rockable between positions in one of which said rounded portion is positioned in contact with said edge of the opening, and in the other of which the rounded portion is positioned edge-wise to said edge of the opening with one side edge of the rounded portion engaged in one of said notches, there being gudgeons extending from opposite ends of the locking shaft and aligned longitudinally and centrally of said ends of the locking shaft, said gudgeons extending into the slots of the holding blocks, the gudgeons being disposed, in the first-named position of the rounded portion, in the vertical slots whereby to disengage the bearing blocks from the holding blocks, said gudgeons in the second-named position of the rounded portion being disposed in the horizontal slots, whereby to lock the bearing blocks to said holding blocks.

JOHN V. GUNN.
